UNITED STATES PATENT OFFICE

WILLIAM ERASTUS WILLIAMS, OF WILMETTE, ILLINOIS, ASSIGNOR TO DITTO, INCORPORATED, OF CHICAGO, ILLINOIS, A CORPORATION OF WEST VIRGINIA

HECTOGRAPH COPYING MACHINE

Application filed August 25, 1927. Serial No. 215,381.

My machine relates to that class of hectograph copying machines wherein a gelatin pad is made in sheet strip form and carried on spindles attached at each end of the sheet strip and the machine is provided with an impression bed and means for holding spindles at each end of the bed and drawing the gelatin pad from one spindle over the bed and winding it on a spindle at the other end 10 of the bed in connection with a movable carriage carrying an impression or platen roll adapted to impress paper on to the gelatin pad and thereby making copies on the hectograph method.

15 The object of my invention is to improve the construction of the machines of that class in general arrangement and details of parts of the machine in a manner to do more efficient work and to cause the machine to operate with greater precision in registering copies and to regulate the pressure on the gelatin pad and to provide in one machine means of making what are known as marginless copies along with copies which have 20 a somewhat wide margin on the edge of the sheet to be copied and in the peculiar arrangement of the parts which makes, as it were, one machine the combined marginless and standard bar machine.

25 Further, the improvements in the machine relate to the construction of the parts to be more cheaply made and as to repairs and renewals of the parts to be more easily made by people who are not necessarily so-called 30 mechanical experts and these features will be described in the specifications in more detail and set forth in the claims.

Reference will be had to the accompanying drawings in which Figure 1 is a side elevation of the entire machine looking from the left side of the machine, the carriage being in an upward position for the admission of the gelatin pad.

Figure 1A is an elevation of the near end 45 of the frame.

Figure 2 is a plan sectional view of the machine on line 2—2 of Figure 1.

Figure 2A is a side elevation of one end 50 of a spring that holds one end of the roll spindles.

Figure 3 is a plan view of the near end of the carriage and frame when the carriage is back in the position whereat it receives the paper for the copy.

Figure 4 is an end sectional elevation on line 4—4 of Figure 5.

Figure 5 is a side elevation of the carriage at the near end of the machine looking from the right side and with the right side frame member removed. The position of the carriage of Figure 5 being that after the carriage has started forward and commenced to make the copy.

Figure 5A is a plan detail of a shaft bearing to be described later on line 5A—5A of Figure 5.

Figure 6 is a sectional elevation on line 6—6 of Figure 3 through the carriage when the same is in position of first application of the paper to the gelatin pad when the machine is in position using the standard margin bar.

Figure 7 is a sectional detail elevation similar to that of Figure 6 showing the locking means of holding the platen roller down during the making of the copy.

Figure 8 is a transverse sectional elevation on line 8—8 of Figure 3 showing the position of the parts in the same position as that of Figure 6 but looking from the left side toward the right, whereas in Figure 6, the view is from the right side toward the left. Thus Figure 6 shows the left end of the platen roll connections, while Figure 8 shows the right end of the platen roll connections on the same line as that of Figure 8.

Figures 8A and 8B relate to a swivel joint connection to platen roll bearing.

Figure 9 is a similar view to that of Figure 8, but showing the carriage after it has started forward in making the copy. The position of the parts of Figure 9 is substantially what is shown in Figure 5.

Figure 9A is a detail of a section through shaft 83 and hub 100 of arm 94 on line 9A—9A of Figure 9B.

Figure 9B is a plan of the hub 100 of arm 94.

Figure 10 is a similar view to that of Figure 8 on the same section line, but shows the 100

platen roll in an elevated position, being the position in which the paper is fed and registered ready for taking a copy.

Figures 10A and 10B are details to be described later.

In Figures 5, 6, 8, 9 and 10, the machine is set for use with what is termed the standard margin bar and with this setting of the machine, the copy is not made clear to the end of the paper sheet, but a short distance is blank, being the distance across the width of the horizontal face of the margin bar.

Figure 11 shows the machine adjusted to use what is termed the marginless margin bar and the standard margin bar is revolved back out of the way in a neutral position, whereas in Figures 5, 6, 8, 9 and 10, the marginless margin bar is in a neutral position and out of the way permitting the free use of the standard margin bar. The section shown in Figure 11 is looking from the right toward the left.

Figure 12 is a similar view to that of Figure 11, showing the platen roll pressing the paper sheet to contact with the gelatin pad, whereas in Figure 11 the paper has been inserted in position on the margin bar just prior to the descent of the platen roll and Figure 12 shows the platen roll down at the commencement of making a copy.

Referring now to the drawings, the machine is provided with any suitable frame having feet or supporting standards 1, which are shown as being fastened by bolts 2 to side frames 3 and 4 of the machine. These side frames are connected together by angle strut braces 5 and 6, see Figures 1 to 4 inclusive. These side frames are stiffened by being offset at 7 in the middle portion of the frame. There are also stiffening flanges 8 at the bottom and narrow flanges 9 at the top. The side frames and the angle strut braces form, as it were, the main frame of the machine.

The gelatin pads used with the machine are in the form of sheets wound in rolls carried on spindles, the roll of gelatin pad being indicated by 10 and the spindles by 11.

The spindles 11 are provided with gudgeons 12 having trunnion pin ends 13 which are held and supported in the right side frame 3 by spring arms 14 provided with perforations 15 into which the trunnion ends 13 engage—see Figure 2A. The spring 14 is curved at its protruding end and is cut-in and embossed on the inclined lines 16 to form a guideway to assist in springing in the spindle ends into the perforations 15. The other ends of the spring 14 are fastened by bolts or rivets 17 to the cross struts 5 and 6.

The other ends of the spindles 11 are carried in apertures and cross slots in the ends of short shafts 18 and 19 at the left of the machine see Figure 2. The shafts 18 and 19 are carried at their inner ends in perforations 20 in housing blocks 20 and 21, the latter being

secured by screws 22, see Figure 1,—to the left side frame 4. Mounted on the shafts 18 and 19 are ratchet wheels 23 and 24 by means of which the shafts 18 and 19 are limited in movement by the aid of pawls 25 and 26. The pawls are hinged in the housings 20 and 21 and in the side frame 4.

On the shaft 18 there is a hand wheel 27 by means of which the shaft 18 is revolved as desired in winding the gelatin pad sheet on the spindles. When desired, a similar hand wheel to that of 27 is put upon the shaft 19 for winding the gelatin pad sheet on the outward spindle 11.

The pawl 25 engages by gravity since its outer end is long enough to overbalance the inner engaging end and on the side of this outer end there is secured a flat spring 28, showing in dotted lines in Figure 2 which engages a notch 29 (see Figure 1A) in the end of the flange of side frame 4 and holds the pawl 25 out of engagement when desired. Clearance space below the notch 29 allows the spring and outer end of the pawl 25 to vibrate as the ratchet revolves in winding the gelatin pad on to the frame spindle 11.

The pawl 26 has its catch in the form of a hook, as it were, and has connected to its shaft an arm 30 which is engaged by a thin flat bar 31 which rests on the offset 7 of the side frame 4 and extends to the region of the hand wheel 27 when it engages an arm 32 on a short shaft 33 hinged in the housing 20 and the side frame 4 and the shaft 33 extends outside of the housing 20 and has mounted thereon a small hand lever 34 in convenient reach of the hand of the operator when he operates the hand wheel 27. Thus as desired, the operator may release the pawl 26 and draw the gelatin band over from the rear spindle to the front or near spindle as desired and by engagement of both pawls 25 and 26, he may draw the band taut over the impression bed 35 of the machine.

The impression bed 35 is composed of a flat sheet of steel or other suitable metal and is bound on its lower marginal edges by strips of wood 36 or other material into which carpet tacks may be driven and over the top and edges of the impression bed there is stretched a sheet of felt cloth 37 or other suitable material and this felt is stretched over the wood strips 36 and is tacked thereto.

At desired intervals along the length of the impression bed at each side thereof see Figures 4 and 6, there are secured to the impression bed plate 35 small metal blocks 38.

Through the blocks 38, there pass the bolts or screws which secure the impression bed plate 35 to horizontal flanges 39 of rack rails 40. Said rack rails 40 extend the length of the machine on each side and in between the narrow flanges 9 of the side frames but not in contact therewith but leaving a clearance space indicated as slots 41 between the rack

rails 40 and flange 9 of the side frames 3 and 4. On the outside edges of the rack rails 40 there are downwardly extending flanges 42 on which are rack gear teeth 43.

The rack rails 40 are connected at each end to end blocks 44 at the front or near end of the machine and end blocks 45 at the rear. (See Figures 1, 1A, 5 and 6.) The blocks 44 are set vertically and blocks 45 are at an incline and these end blocks are fastened by screws 46 and 47 to the rack rails and by screws 48 and 49 to a set of track bars 50.

The track bars 50, end blocks 44 and 45, rack rails 40 and impression bed plate 35, when fastened together as described, make a secondary frame unit on which is mounted the impression carriage which impresses the paper to the impression bed.

This secondary frame is fastened by screws 51 to the side frames 3 and 4, the lower ends of the end blocks 44 and 45 resting on the offsets 7 of side frames.

By means of the two frames, as it were, the secondary frame permits the impression carriage to be assembled and adjusted to the secondary frame when the latter is free from the main frame.

The gelatin pad sheet is trained over the impression bed and the copy is made off of the portion 52 that is open on the bed, which portion is properly moistened by the operator by any suitable means.

The paper containing the master copy and the paper to receive copy are impressed on its gelatin portion 52 by a platen impression roll 53 carried in an impression carriage.

The impression carriage is provided with a cross frame member 54, see Figure 6, having a downwardly extending stiffening flange 55 and upwardly extending end flanges 56, which end flanges are stiffened on their edges by turned over flanges 57. The ends of the cross frame member are also stiffened by downwardly extending transverse angle pieces 58 riveted to the cross member 54.

To the end flanges 56, there are secured downwardly extending legs 59, which ride on trunnion ends 60 of a cross shaft 61, on which there are fixed two gear wheels 62, which engage the rack gear teeth 43, and by this means, the carriage is held squarely across the impression bed in all the outward and back movements of the carriage.

The weight of the carriage as supported by the legs 59 is carried on flanged wheels 63 running loosely on shaft 61 and held in position on the said shaft by the gear wheels 62 at one side and by set collars 64 on the other side.

The carriage is also supported at each end by peculiarly shaped end castings having curved upwardly extending arms 65 from and integral with longitudinal arms 66, the ends of which are connected on the trunnion ends

The castings are fixed at 68 (see Figure 4) to a cross bar shaft 67 which acts as a beam and a strut to hold the end castings in position.

Mounted to revolve loosely on shaft 67 are flanged wheels 69 which ride on the track bars 50. The wheels 67 are held in place by set collars 70.

The curved arms 65 and the legs 59 pass through the apertures or spaces 41 between the side frames 3 and 4 and the rack rails 40.

The arms 65 are offset to pass outside of the legs 59 and are provided with shoulders 71 (see Figure 5) on which the legs 59 rest and thus support the carriage when the same is in position of making copy.

The end castings are provided with lip projections 72 which extend under the track bars 50 and thus hold the end castings always down with the flanged wheels 69 in contact with the track bars 50.

When the carriage is in position of Figure 5, it is held in that position in relation to the end castings by means of catch blocks 73 engaging notches 74 in arms 65. There are two of the catch blocks 73—one on each end of the carriage and are fixed on a cross shaft 75 extending underneath the cross frame 54 and fixed to this cross shaft 75 there is a lever arm 76 (see Figure 6) through the end of which there passes a bolt 77 over which there is a coil spring 78 which acts to hold the catch blocks 73 in contact with the notches 74 in arms 65. Small knobs 79 on catch blocks 73 enable the operator to disengage the catch blocks 73 from the notches 74 and lift the carriage from the position of Figure 5 to that of Figure 1. In which position of Figure 1, there is clearance to permit the passage of the spindles 11 over the impression bed and through and underneath the impression carriage in the service of removing and replacing rolls of the gelatin pad in the use of the machine.

When the impression carriage is in the position of Figure 1, it is held in repose in that position by means of pins 80 which abut against the end of flanges 57 to prevent further uplift of the carriage and detent levers 81 hinged at 82 to the end flanges 56 which levers also engage the pins 80 and hold the carriage upward. As desired, the operator releases the detent levers and lowers the carriage for copy position.

Extending across between the end flanges 56 of the impression carriage, there is a shaft 83 apertured at its ends into which stud plugs 84 (see Figure 5A) enter and are fixed therein by pins or other means and furnish the bearings for shaft 83 in the carriage frame.

The stud plugs 84 are threaded in their ends for the use of a tool to assist in their withdrawal when it is desired to take out the shaft 83 from the carriage.

The platen or impression roll 53 is prefer-

ably faced with rubber 85 and is provided at one end with a fixed bearing trunnion 86, (see Figure 4) and at the other end is provided with a slidable trunnion end 87, held in a tubular end of the roll and held in an outward position by a spring 88 and prevented from being pushed out by the spring 88 by a pin 89 passing through a slot 90 in the trunnion 87. The trunnion 87 is carried in a bearing block 91 and the trunnion 86 is carried in bearing block 92, which is a part of an arm 93 (see Figure 6) carried on shaft 83. The bearing block 91 is (see Figures 3, 4, 8, 8A, 8B), is, as it were, connected to its supporting arm 94 by a swivel joint connection, the block 91 having hinge pins 95 held in clasp pieces 96 fixed to a swivel block 97 hinged in arm 94 and held therein by a pin 98 passing along side a groove in the hinge projection of swivel block 97.

When it is desired to remove the platen or impression roller 53, it is pushed lengthwise compressing the spring 88 until the trunnion 86 is free of bearing 92 and then the roll is rocked apast the bearing 92 and pulled out from bearing block 91, the latter moving by its jointed connections to permit the withdrawal of the trunnion block 87. The platen roller 53 is returned in position by similar reverse movements from those in taking it out.

The arms 93 and 94 are provided with hubs 99 and 100 respectively that are free to revolve on shaft 83 through a small arc (see Figures 3, 9A and 9B, 10B) and this arc being limited by pins 101 in shaft 83 moving in slots 102. Thus the arms 93 and 94 may rock on shaft 83 the arc of the slots 102.

The arms 93 and 94 are revolved on shaft 83, the limit of the arc of the slots 102 by coiled springs 103 on shaft 83 (see Figure 3) one end of which springs engage the hubs 99 and 100 and the other ends of the springs 103 engage collars 104 and these collars are provided with teeth 105 which engage similar teeth on collars 103 fixed on shaft 83 by means of pins 107 or any other suitable means. The collars 104 are provided with holes 108 by means of which a spanner wrench may be used to revolve collars 104 and thus tighten or loosen springs 103 by shifting the association of the teeth 105 of the collars 104 and 106. To assist in loosening the teeth of the collars from each other, a few of the teeth of collar 106 are cut away, leaving a notch 109 into which the end of a screw driver or other suitable instrument may be placed and be made by a twisting movement to disengage the teeth of the collars which the spanner wrench moves the collars 104 to tighten or loosen the springs 103.

The springs 103, collars 104 and 106 are normally covered up by tubular thimbles 110 and 111 for purposes of appearance and to

defend against maladjustment of the springs by curious operators. The thimble 110 at left of Figure 3 is shown slipped off of the collars while the thimble 111 is in place covering up the springs 103, collars 104 and 106 on that end of the carriage.

The shaft 83 is operated in a rocking movement by an operating lever 112 having a hand hold ball 113 by means of which the shaft is rocked moving the platen or impression roll 53 to and from the impression bed.

The shaft 83 is limited in its movement by an arm 114 (see Figures 3 and 7) at the left of Figure 3, which arm is fastened to shaft by any suitable means and a pin 115 limits the rocking movement of shaft 83 by the arm engaging said pin 115 at the forward end of its arc of movement. The stop pin 115 is so placed that the rocking of the shaft 83 by the operator is stopped just before the platen roll 53 is pushed onto the impression bed to the limit of the arc or range of movement of the springs 103 as described. Thus the actual pressure of the roll 53 in placing paper on the gelatin pad sheet on the impression bed is only that produced by the springs 103.

The pressure may be adjusted as desired by the adjustment of the spring 103 as described.

After the paper has been laid down for copy on the impression bed by rocking forward, the operating lever 112 and the carriage moved forward slightly, the arm 114 in contact with pin 115 is locked in that position by a series of bell crank levers 116 hinged on a stud pin 117 in the left end flange of the carriage frame and levers 116 have engaging teeth 118 which vary as to each lever to insure an engagement with the arm 114 without slack or play as relates to the contact of arm 114 with pin 115.

The lower ends 119 of levers 116 are adapted to abut against a stop block 120 at left side of the machine and release the arm 114 whenever the carriage is borne at the place when paper is put in place and removed from the carriage.

A similar stop 121 is located at the right of the frame and these stops are faced with rubber cushioning blocks 122.

The stop blocks 120 and 121 are mounted on the rack rails 40 and are adjustable longitudinally thereon and held in place by set thumb screws 123—however, certain locations such as the one whereat the standard margin bar and the marginless margin bar is used, holes 124 are drilled into the tops of the rack rails, shown in dotted lines in Figure 6 and the points of the screws 123 are set into these holes for security of location of the stop in exact registration as desired.

When the carriage is moved out away from the stops in making copy, the levers 116 are free to fall and lock the arm 114 and thereby

the shaft 83 and hold the impression roller 53 down on the copy until the carriage returns and the lower ends 119 of the levers 116 again abut against the stop 120 and release the shaft 83 to be rocked by the hand operating lever 112 in lifting the impression roll 53 free of the copy for a new cycle of operation.

The paper 125 for copy is placed in the machine in position of registration with its bottom edge in position on the standard margin bar 126, as shown by dotted lines in Figure 10 and then the operator rocks the impression or platen roll 53 downward bringing the paper 125 to contact with the gelatin pad at 52 on the bed 35 and in this movement the roll 53 pushes the paper into contact with a compression roll 127 which is mounted in bearings in blocks 128 which are hinged at 129 and are provided with arms 130 through which bolts 131 pass downward through the cross frame 54 of the carriage and have mounted thereon springs 132 which hold the compressing roll 127 to hold the paper in contact with the impression roll 53 to assist in drawing or lifting the paper from the gelatin pad on the return movement of the carriage.

As the impression roll moves downward in the function of passing the paper from Figure 10 to that of Figure 6, the contact with the compression roll 127 as roll 53 moves by it has a tendency to revolve the roll 53 and thus displace the paper from registry of the margin bar, and to insure against such displacement, there is provided means for holding the impression roll 53 from revolving and thus preventing such displacement.

The means for preventing this displacement may be by any suitable device such as a friction brake on the roll 53, but there is here shown a ratchet 133 on the roll 53 and this ratchet is engaged at a desired location of the carriage by a two toothed pawl 134 which is hinged at 135 to the hub 100 of arm 94 and drops by gravity to engagement with the ratchet 133 at all times when the carriage is at home against the stops 120 and 121 being the only location whereat the paper is placed in position of registration for copy and the only place where the roll 53 is moved to contact with the compression roll 127.

When the carriage is moving out and back in the function of making the copy, the pawl 134 is lifted free of the ratchet 133 to permit the free revolution of the roll 53 in making copy. The pawl 134 engages the ratchet when the carriage is against the stops and is free from the ratchet when the carriage is away from the stops.

The movement of freeing the pawl 134 from the ratchet 133 is produced by a spring 136 (see Figure 5) on a bolt 137 which passes through the flange 57 at the right end of the

carriages and through a lip 138 on a bell crank lever 139 hinged at 140 to the right end of the impression carriage. As best observed in Figures 3, 8 and 9, the lever 139 is provided with a projection 141 which engages the end of a pin 142 of pawl 134 and this arrangement permits the spring 136 to lift the pawl 134 clear of the ratchet 133 when the carriage is moved away from the stops 120 and 121, but when the carriage is home against the said stops an arm 143 on lever 139 abuts against stop 121 and compresses spring 136 and moves the projection 141 clear of pin 142 of pawl 134 which allows gravity to engage the pawl to the ratchet 133 which it does do at all times when the impression carriage is home against the stop 121 and thus hold the roll 53 from moving to displace the registration of the paper on the margin bar.

To prevent the pawl 134 from being lifted too far from the ratchet 133, there is provided a stop catch 144 fastened to arm 94 by screw 145 and provided with a catch lip 146 which limits the uplift of pawl 134.

The pawl 134 is made with two teeth—one main tooth and a secondary tooth hinged at 147 to main tooth and limited in movement in relation to main tooth by a pin 148 in main tooth in a slot 149 in secondary tooth (see Figure 9) and the teeth are shorter in relation to each other by the distance of one-half the space of one ratchet tooth. So as to catch the ratchet at one-half tooth spaces, more than two teeth may be used when desired to catch smaller distances on the ratchet.

The standard margin bar 126 is provided with arms hinged at 151 to side frames of the machine when not in use and when a new roll spindle 11 is to be introduced, this bar 126 is placed back in position shown by Figures 11 and 12.

When copies are desired to be made at or close to the margin of the paper, a marginless margin bar is used. See Figures 11 and 12 wherein 152 indicates the marginless margin bar which is provided with an arm 153 at its left end hinged at 154 to left end of carriage frame. A similar arm 155 at the right end of the bar 152 is hinged at 156 to the right end of carriage frame (see Figure 8). The left arm 153 has an upper extension 157 and is provided with corners 158 adapted to be engaged by a locking catch 159 hinged at 160 and this catch is held into engagement by a flat spring 161 which bears on the cross frame of the machine. The upper extension 157 of arm 153 is provided with a pin 162 which passes through a slot 163 in a link 164 which is provided with a slot 165 which rides on a pin 166 in a block 167 secured by a bolt 168 to arm 93 on shaft 83. The slot 165 is a long slot sufficient to allow the shaft 83 to move through

its normal arc without moving the link 164, but when the link 164 is desired to be moved as is necessary in the use of the marginless margin bar 152, the slot 165 is, as it were, 5 shortened by a peculiarly shaped block 169 hinged at 170 to link 164 and provided with an end 171 adapted to shunt off the length of slot 165 and engage pin 166 and thus move the link by said pin at that end of slot 165. 10 When block 169 is not in service, it is moved upward out of the way of pin 166 from position of Figure 11 to that of Figure 6. A coiled spring 172 is fastened to pin 162 and passes through the cross frame and is fastened at 173 to always act to swing the marginless margin bar 152 back from position of Figure 11 to that of Figure 12 when permitted to do so by freeing the locking catch 159 from the corners 158. 15 The freeing of the catch 159 is accomplished by the end 174 of link 164 engaging a pin 175 in catch 159 and lifting the catch from position of Figure 11 to that of Figure 12, as the shaft 83 is moved to bring the impression roller down on the gelatin pad. 20 As soon as the catch 159 releases the spring 172, it instantly begins to move the marginless margin bar 152 back out of the path of travel of the roll 153, but this does not take 25 place until the roll 53 is in contact with the compression roll 127 which then holds the paper in register without the use of the bar 152 so that the latter is then permitted to move back out of the way of roll 53. 30 The movement of the bar 152 by the spring 172 is limited by a cam block 176 on an arm 153 of bar 152 which cam block is engaged at intervals by a pin 177 in arm 93 (see Figures 3, 4, 11 and 12,) which pin 177 is in line with the center of roll 53 and when 35 the marginless margin bar 152 is not in use as is shown by Figures 1 to 10 inclusive, the pin 177 passes free of cam block 176. A function of the cam block 176 is to prevent the spring 172 from throwing the bar 152 backward too quickly and controlling the movement of the bar 152 under the influence of the spring 172, to the end that the bar 152 will stay in the position of Figure 11 until 40 the roll 153 has descended to contact the paper 179 with the roll 127. This is brought about by the pin 177 passing down on the under inclined side of the cam block 176 until this pin 177 has passed below the lower end of the cam block 176, and thereupon the spring 172 instantly throws the bar 152 to a retreated position indicated by Figure 12. Then on the raising of the roll 53 from the 45 position of Figure 12 to that of Figure 11 the pin 177 passes on the upper side of the cam block 176, ready for a fresh operation. the latch 159 holding the arm 153 to the position of Figure 11 until it is released by a new 50 operation of moving down the roll 53, when 55 again the pin 174 of the link 164 engages the

pin 175 and releases the catch 159, whereupon the pin 177 at that position of the parts is engaged on the under side of the block 176.

In placing the link 164 on the pin 166, a notch 178 is provided to admit pin 166 to slot 165 (see Figure 12).

The functioning of marginless margin bar 152 is as follows:

The operator lifts the roll 53 from Figure 12 to that of Figure 11 and thus sets the bar 152 in position of Figure 11 and on descent of roll 53 the spring 172 sets the bar 152 at position of Figure 12 and when bar 152 is not in use the parts stay in position of Figures 1 to 10 inclusive.

The paper in Figures 11 and 12 is indicated by 179.

The cross frame 54 of the impression carriage acts as the paper guide to the margin bars and a side guide for the paper is provided in the form of a plate 180 having a flange 181 and this guide plate is adjusted across the carriage by hand and locked in position by a small cam lever 182 in a downward flange 183 of plate 180 which flange 183 extends over and is bent under the flange 55 of cross frame 54.

In machines of this class the gelatin pad is necessarily soft and sometimes in hot humid weather the gelatin gets so soft that it gums up the platen roll and at all times some little gumming up of the platen roll takes place due in part to lint or coating from the paper and ink used to the end that it is necessary to wash and clean the platen roll and it is of importance that the means for holding the platen roll in the carriage be such that the roll may be easily and quickly removed and replaced and the means here shown are especially important in that respect.

Heretofore, it has generally been the practice to build machines to use either the standard margin bar or the marginless margin bar as separate machines or in some cases, as it were, converting one machine into the other by changes and removal or substitution of a considerable number of parts, certain parts always being taken off and stored when not required in service of one or the other machine. This method is objectionable as it consumes time in changing the parts and the loose and unused parts are frequently lost or misplaced and the trouble of changing from one margin bar to the other more or less defeats the purpose of the use of one or the other type of machine. The arrangement of this machine wherein it takes but a moment to change from one bar to the other is a great desideratum and is made possible in part by the arms 93 and 94 which carry the platen roll being so shaped as to provide clearance underneath them for the marginless margin bar to pass and stay under the said arms when the marginless mar-

gin bar is out of service or in retreated position for if this marginless margin bar is to remain in the carriage while the standard margin bar is used, it must be so placed in 5 retreat as to clear the standard margin bar when the latter is used and this position is best observed in Figure 6 wherein 184 indicates the clearance of the arms 93 and 94 brought about by the upward shape of the 10 said arms in passing from the platen roll bearings to the shaft 83 instead of straight connections thereto.

The rack teeth 43 of the flanges 42 of rack rails 40 are shown in Figure 5 and extend 15 the full length of and on both sides of the bed, but they are not drawn in full in the other figures. This is likewise true of the gear teeth of gear wheels 62.

What I claim is:

20 1. In a hectograph copying machine, an impression bed adapted to have a hectograph gelatin sheet trained thereover, a carriage carrying a platen roll and a compression roll, the latter adapted to compress paper to 25 the platen roll, and means for bringing the two rolls together and for reciprocating the platen roll to the impression bed and the latter means provided with springs arranged to press the platen roll on to the impression bed 30 in yielding elastic contact to accommodate unevenness in the bed and varying thickness of paper and gelatin sheet, and limiting means for limiting movement of said first mentioned means toward said impression bed 35 to a region spaced from said bed a distance less than the range of action of said springs.

2. In a machine of the class described, an impression bed, a platen roll adapted to impress paper on the impression bed, said platen roll mounted in bearings in arms mounted 40 on a rocker shaft and said arms provided with spring connections to said rocker shaft.

3. In a machine of the class described, an impression bed, a carriage including a platen 45 roll adapted to impress paper on the impression bed, means for reciprocating said platen roll relative to said carriage and holding the said platen roll to the said bed, said means including a rocking member and springs between said rocking member and said platen 50 roll, and limiting means for limiting the rocking movement of said rocking member to a region such that said springs may not be actuated to the limit of their range.

55 4. In a machine of the class described, an impression bed, a platen roll adapted to impress paper to the said bed, a rocker shaft adapted to carry the said platen roll and 60 raise and lower the same in relation to the said bed, said platen roll having bearings and springs interposed between said bearings and said rocker shaft, and means for limiting the movement of said rocker shaft to a predetermined region whereby the roll is permit-

ted to adjust itself to the bed by elastic contact.

5. In a machine of the class described, an impression bed, a platen roll adapted to impress paper to the bed, a rocker shaft providing the means for being rocked thru an arc, arms mounted on said rocker shaft and adapted to be revolved thereon thru an arc, spring connections between the said shaft and said arms and bearings in said arms for carrying the said platen roll. 75

6. In a machine of the class described, an impression bed, a carriage, said carriage including a platen roll, and movable means supported by said carriage for holding said platen roll, said holding means including spring connections interposed between said platen roll and the remainder of said holding means, and adjustable means for holding said holding means in a position adjacent to said bed. 80

7. In a machine of the class described, an impression bed, a platen roll adapted to impress paper to the said bed, a rocker shaft having arms in which are bearings for carrying the said platen roll, said arms engaged to be moved by springs on the said rocker shaft, collars on said shaft adapted to assist in adjusting the pressure of said springs. 90

8. In a machine of the class described, an impression bed, a platen roll mounted and adapted to impress paper to the said bed, a rocker shaft adapted to carry and move said platen roll to and from the said bed, means for limiting the movement of said rocker shaft to prevent excess pressure of said platen roll on said bed and spring connections between the said rocker shaft and said platen roll whereby the spring connections hold the said platen roll to the said bed after the limit of movement of said rocker shaft has been reached. 100

9. In a machine of the class described, an impression bed, a platen roll mounted to impress paper on said bed, a rocker shaft provided with arms adapted to carry said platen roll, said arms mounted to revolve on said rocker shaft thru a small arc and prevented from moving more than said arc, fixed collars 110 on said rocker shaft, and movable collars also on said shaft in relation to said fixed collars, means for adjusting the said movable collars in relation to said fixed collars, springs interposed between the said movable collars and said arms whereby the arms are moved thru their arcs of movement by the said springs, means for limiting the movement of said rocker shaft after the said platen roll is in contact with the impression bed. 115

10. In a machine of the class described, an impression bed, a platen roll mounted to be moved to and from the said bed, a rocker shaft adapted to carry said platen roll, an arm fixed on said rocker shaft, a series of 120

levers alternatively adapted to lock the said arm in selectable positions determined by the thickness of the gelatin sheet and paper being operated upon.

5 11. In a machine of the class described, an impression bed, a platen roll mounted to be moved to and from the said bed, a rocker shaft adapted to carry said platen roll, an arm fixed on said rocker shaft adapted to engage a stop pin to limit its movement in carrying the said platen roll to the bed, a series of levers adapted to lock the said arm against said stop pin, spring connections for the bearings of said platen roll in relation to the said rocker shaft.

10 12. In a machine of the class described, an impression bed, a platen roll mounted to be moved to and from the said bed, a rocker shaft adapted to carry said platen roll, an arm fixed on said rocker shaft adapted to engage a stop pin to limit its movement in carrying the said platen roll to the bed, a lever adapted to lock the said arm against said stop pin, spring connections for the bearings of said platen roll in relation to the said rocker shaft.

15 13. In a machine of the class described, an impression bed, a platen roll adapted to contact with said bed in making copies, said roll having a trunnion adapted to slide endwise in combination with a trunnion bearing block hinged to allow a rocking motion of said trunnion to facilitate the entrance and removal of the said trunnion from said bearing.

20 14. In a machine of the class described, an impression bed, a platen roll adapted to impress paper on the said bed and provided with a trunnion adapted to slide endwise and a spring adapted to hold the said trunnion in operative position, in combination with a trunnion bearing block hinged to allow a rocking motion of said trunnion to facilitate the entrance and removal of the said trunnion from said bearing.

25 15. In a machine of the class described, an impression bed, a platen roll adapted to impress paper on the said bed, a slideable trunnion adapted to assist in taking out and replacing the said platen roll; in combination with a bearing block mounted to swivel and facilitate the taking out and replacement of said platen roll.

30 16. In a machine of the class described, an impression bed, a platen roll adapted to impress paper on the said bed and provided with a slideable trunnion sliding endwise within an aperture in said roll, a slot in the said trunnion and a pin passing thru the said slot to hold the trunnion in place and a spring within the said aperture of said roll and acting on said trunnion to eject the same, in combination with a trunnion bearing block hinged to allow a rocking motion of said trunnion to facilitate the entrance and removal of the said trunnion from said bearing.

35 17. In a machine of the class described, an

impression bed, a platen roll adapted to impress paper on the said bed and provided with a slideable trunnion sliding endwise within an aperture in said roll, a slot in the said trunnion and a pin passing thru the said slot to hold the trunnion in place and a spring within the said aperture of said roll and acting on said trunnion to eject the same; in combination with a swivel hinged bearing for the said trunnion bearing of said platen roll.

40 18. In a machine of the class described, an impression bed, a platen roll adapted to impress paper to the said bed, a bearing for said platen roll having a universal joint connection in which it is mounted; in combination with a yielding journal end whereby the platen roll may be disengaged from its bearings by an endwise movement.

45 19. In a machine of the class described, an impression bed, a platen roll mounted to impress paper on the said bed, a marginless margin bar hinged to swing to and from position of registration of the paper, a spring adapted to move and hold said marginless margin bar in retreat out of and away from said registration position and positive means for moving the said marginless margin bar into registration, a catch for holding the said marginless margin bar in position of registration and means for disengaging said catch and thereby releasing the said spring to move said marginless margin bar back to position of retreat.

50 20. In a machine of the class described, an impression bed, a platen roll mounted to impress paper on the said bed, a marginless margin bar hinged to swing to and from position of registration of the paper, a spring adapted to move and hold said marginless margin bar in retreat out of and away from said registration position and positive means for moving the said marginless margin bar into registration, a catch for holding the said marginless margin bar in position of registration and means for disengaging the said catch and thereby releasing the said spring to move said marginless margin bar back to position of retreat; in combination with a standard margin bar in association with the frame of the machine and adapted to be into and out of service alternately as desired in making standard copies or marginless margin bar copies.

55 21. In a machine of the class described, an impression bed, a platen roll adapted to impress paper to the bed, a marginless margin bar hinged to be swung into and out of position of registration of the paper to the bed, positive means for swinging the said bar to position of registration and spring means for moving the said bar in retreat from position of registration, a catch for holding said bar in position of registration and means for releasing said catch, a cam block for limiting and guiding the time of retreat movement of

said bar under the control of said spring movement.

22. In a machine of the class described, an impression bed, a platen roll adapted to impress paper to the bed, a marginless margin bar hinged to be swung into and out of position of registration of the paper to the bed, positive means for swinging the said bar to position of registration and spring means for moving the said bar in retreat from position of registration, a catch for holding said bar in position of registration and means for releasing said catch, a cam block for limiting and guiding the time of retreat movement of said bar under the control of said spring movement; in combination with means for disengaging the said positive moving means for said bar.

23. In a machine of the class described, a marginless margin bar hinged to swing to position of registration for the paper and to swing outward in retreat clear of the platen roll, positive means for swinging the said bar into registration position and a spring movement for swinging it to retreating position and said positive means composed of a link connection and said link having a slotted end and means for shutting off the length of the said slot.

24. In a machine of the class described, a marginless margin bar hinged to swing to position of registration for the paper and to swing outward in retreat clear of the platen roll, positive means for swinging the said bar into registration position and a spring movement for swinging it to retreating position and said positive means composed of a link connection and said link having a slotted end and means for shutting off the length of the said slot and said means for shutting off the length of the said slot composed of a hinged block hinged to the said link and adapted to swing across the said slot and to swing clear of the same.

25. In a machine of the class described, a marginless margin bar adapted to be swung into registration position and out of and in retreat from said position, positive means for moving the said bar into registration position and spring means for moving into retreat position, a catch adapted to hold said bar in registration position, a link connection for moving the said bar positively and said link provided with slots at each end and the slot at one end adapted to permit the said link to act to disengage the said catch at the desired time and the slot at the other end of said link adapted to permit the said bar to be moved by the said spring whenever the said catch is released as aforesaid.

26. In a machine of the class described, a marginless margin bar hinged in the carriage frame of the machine, a platen roll carried in the said carriage frame by means of arms extending from a rocker shaft mounted in

the said carriage and extending over said margin bar, said arms having clearance spaces on their under sides for the passage of said marginless margin bar and said bar passing underneath the said arms.

27. In a machine of the class described, a marginless margin bar hinged to swing into and out of registration position in association with a platen roll, said bar having a cam block attached to swing with the said bar, a contact pin moving with said platen roll to engage the said cam and said cam adapted to engage with the said pin in the retreat movement only of the said bar and so shaped that when said bar is in retreated position the said pin will pass on the other side and free of said cam.

28. In a machine of the class described, a marginless margin bar hinged in the carriage of the machine and adapted to swing into registration position and out into retreated position; in combination with a standard margin bar hinged to the main frame of the machine and adapted to be swung into registration position and out in retreated position, the said marginless margin bar when in retreated position located above and clear of the top of the standard margin bar when the latter is in registration position.

29. In a machine of the class described, a carriage carrying a platen roll adapted to impress paper to an impression bed, means for raising and lowering the said platen roll in relation to said bed, a compression roll adapted to compress paper to the said platen roll, a margin bar for registering the paper in relation to said bed, means for preventing the revolution of said platen roll in the movement of compressing paper in first contact with said compression roll and bed and means for releasing the said platen roll to revolve as the said carriage is moved out in making copy.

30. In a machine of the class described, an impression bed, a carriage adapted to move over the said bed and having a platen roll mounted therein in a manner to be moved to and from the said bed, a margin bar located across the said bed, stops for arresting the movement of the said carriage in desired registering position for making copy, means for preventing the revolution of the said platen roll at all time when the said carriage is in contact with said stops and means for releasing the said platen roll to revolve when the said carriage moves away from the said stops.

31. In a machine of the class described, an impression bed, a carriage adapted to move over the said bed and carrying a platen roll adapted to impress paper on the said bed, means for holding the said platen roll from revolving while the same moves the paper to first contact with the said bed, stops for

holding the said carriage at registering position, in relation to the said bed, means mounted on the said carriage for releasing the said platen roll to permit it to revolve and said releasing means engaged by said stops to hold it from releasing the said platen roll at all times when the said carriage is in engagement with said stops.

32. In a machine of the class described, an impression bed, a carriage mounted to move over said bed, a platen roll carried by said carriage and adapted to move to and from and roll over the said bed a margin bar extending across the said bed, a stop for locating the said carriage in registering position in relation to said bed, a ratchet on the said platen roll, a pawl adapted to engage the said ratchet, a bell crank lever carried by the said carriage and provided with a projection adapted to engage the said pawl, and also provided with an arm adapted to be engaged by said stop, a spring adapted to move said bell crank lever to release the said pawl from the said ratchet when the said carriage is moved away from said stop.

33. In a machine of the class described, an impression bed, a carriage mounted to move over the said bed, a platen roll carried by the said carriage, means for holding the said platen roll in said carriage in a manner to move said roll downward and upward in relation to said bed, means for preventing the revolution of said roll while the same is being moved downward and upward in relation to the said bed and means for releasing the said preventing means as the said carriage moves out in making copy.

34. In a machine of the class described, an impression bed, an impression carriage adapted to move over said bed and impress paper thereon, an impression roll carried by the said carriage, a ratchet mounted on said impression roll, a pawl adapted to engage the said ratchet and provided with a plurality of teeth adapted to engage said ratchet.

35. In a machine of the class described, an impression carriage, a platen roll carried by said carriage, a ratchet on said platen roll shaft, a pawl adapted to engage said ratchet, a lever adapted to engage the said pawl and release the same from the said ratchet, a spring adapted to move said lever, a stop on the frame of the machine adapted to release the said lever from the said pawl.

36. In a machine of the class described, a main frame composed of side frame pieces and cross frame strut bearings; in combination with a secondary frame and the latter provided with rack rails connected to a bed plate and with track bars and said rack rails connected at their ends to end blocks and said end blocks connected to said track bars and the said secondary frame inserted in and connected to the said main frame.

37. In a machine of the class described, a

main frame composed of side frame pieces and cross frame strut bearings; in combination with a secondary frame and the latter provided with rack rails connected to a bed plate and with track bars and said rack rails connected at their ends to end blocks and said end blocks connected to said track bars and the said secondary frame inserted in and connected to the said main frame, said main frame provided with means for holding roll spindles.

38. In a machine of the class described, a main frame composed of side frame pieces and cross frame strut bearings; in combination with a secondary frame and the latter provided with rack rails connected to a bed plate and with track bars and said rack rails connected at their ends to end blocks and said end blocks connected to said track bars and the said secondary frame inserted in and connected to the said main frame, said main frame provided with means for holding roll spindles, and said secondary frame carrying an impression carriage mounted on wheels between the said rack rails and track bars.

39. In a machine of the class described, a main frame having side frame members of uniform thickness stiffened crosswise by marginal top and bottom inwardly extending flanges and offset portions running lengthwise of the frame, said offset portions being intermediate of the top and bottom flanges, the lower portions of said frame members being narrower than the upper portions thereof.

40. In a machine of the class described, a main frame having side frame members of uniform thickness stiffened crosswise by flanges and offset portions running lengthwise of the frame; in combination with a secondary frame having a bed plate and the said secondary frame connected to the main frame at the ends only of the frames leaving a clearance space alongside the outside of the secondary frame and the inside of the main frame.

41. In a machine of the class described, a main frame having side frame members of uniform thickness stiffened crosswise by flanges and offset portions running lengthwise of the frame; in combination with a secondary frame having a bed plate and the said secondary frame connected to the main frame at the ends only of the frames leaving a clearance space alongside the outside of the secondary frame and the inside of the main frame; in combination with an impression carriage carried in the secondary frame and supported by legs extending down outside the secondary frame and inside the main frame to wheels supported in the secondary frame.

42. In a machine of the class described, a main frame having side frame members of uniform thickness stiffened crosswise by

flanges and offset portions running lengthwise of the frame; in combination with a secondary frame having a bed plate and the said secondary frame connected to the main frame at the ends only of the frames leaving a clearance space alongside the outside of the secondary frame and the inside of the main frame; in combination with an impression carriage carried in the secondary frame 5 and supported by legs extending down outside the secondary frame and inside the main frame to wheels supported in the secondary frame and means mounted in the main frame for supporting roll spindles in a manner to 10 wind the gelatin pad from spindle to spindle at the ends of the frame.

43. In a machine of the class described, a frame wherein there are rack rails running along the sides thereof and having flanges on 15 their inner sides adapted to be connected to a bed plate, and having downwardly extending flanges on their outside edges on which there are rack gear teeth and a bed plate mounted between the said rack rails.

44. In a machine of the class described, a frame wherein there are rack rails running along the sides thereof and having flanges on their inner sides adapted to be connected to a bed plate, and having flanges on their 20 outside edges on which there are rack gear teeth and a bed plate mounted between the said rack rails; in combination with track bars located beneath the said rack rails and parallel therewith.

45. In a machine of the class described, a frame wherein there are rack rails running along the sides thereof and having flanges on their inner sides adapted to be connected to a bed plate, and having flanges on their 25 outside edges on which there are rack gear teeth and a bed plate mounted between the said rack rails; in combination with track bars located beneath the said rack rails and parallel therewith and an impression carriage carried on wheels between the said rack rails and track bars.

46. In a machine of the class described, a frame provided with rack rails having side flanges to which a bed plate is attached, a bed 30 plate attached to said flanges and said rack rails having downwardly extending outside flanges and with rack gear teeth in said flanges.

47. In a machine of the class described, a frame provided with rack rails having side flanges to which a bed plate is attached, a bed plate attached to said flanges and said rack rails having downwardly extending outside flanges and with rack gear teeth in said 35 flanges; in combination with an impression carriage supported by the said frame and having gear wheels engaging the said rack teeth of said rack rails.

48. In a machine of the class described, a frame provided with rack rails having side 40

flanges to which a bed plate is attached, a bed plate attached to said flanges and said side rails having downwardly extending outside flanges and with rack gear teeth in said flanges; in combination with an impression carriage supported by the said frame and having gear wheels engaging the said rack teeth of said rack rails, and stops secured to said rack rails for limiting the movement of said carriage along said rack rails and bed. 70

49. In a machine of the class described, an impression bed, a carriage mounted over and across the said impression bed and carrying a platen roll, said carriage having a frame extending over and across the said bed, extension legs on the ends of said frame extending downward and supported on a cross shaft extending across and underneath the said bed, gear wheels on said cross shaft, racks into which said gears mesh, a cross bar shaft 80 also extending across and underneath the said bed and provided with wheels adapted to roll idle on rails of the frame, arms extending upwardly from the said cross shaft and aside the ends of said carriage frame and arms extending from said cross bar shaft extending to the said first mentioned shaft on which said gears are located, said upwardly extending arms assisting in supporting the said carriage in the frame of the machine, said carriage adapted to be raised bodily about said first mentioned shaft as a hinge to provide clearance underneath the said carriage for the admission of the gelatin pad sheet, with means for supporting the carriage in 90 upward clearance position and down in operative position by connections to said upwardly extending arms.

50. In a machine of the class described, an impression bed, a carriage adapted to move 105 over said bed and impress paper thereon, cross shafts extending across and underneath the said bed from which said carriage is supported, gear wheels and flanged wheels supporting and guiding the said cross shafts in 110 the frame of the machine, the said carriage hinged in relation to one of said cross shafts, whereby the said carriage may be raised above the bed for clearance purposes of admitting the gelatin pad sheet, and means for locking the said carriage down in operative copying position in relation to the said bed. 115

51. In a machine of the class described, an impression bed, a carriage mounted over and across said bed, and adapted to be raised 120 bodily upwardly from said bed for clearance purposes and means for locking said carriage down in operative copying position, and said locking means provided with catches at each end of said carriage and connected on 125 a shaft extending across the frame of the machine and operated simultaneously.

52. In a machine of the class described, an impression carriage adapted to be moved over the said bed in making copies and supported 130

on cross shafts extending across and underneath the said bed and said cross shafts mounted on wheels riding on tracks in the frame of the machine, upwardly curved arms extending up from the said cross shafts and over the ends of said carriage and means for locking the carriage to the said upwardly curved arms.

5 Signed at Chicago, in the county of Cook and State of Illinois this 12th day of August, 10 1927.

WILLIAM ERASTUS WILLIAMS.
